UNITED STATES PATENT OFFICE.

LOUIS K. SONE, OF NEW YORK, N. Y.

COLLAPSIBLE STAND FOR CHAFING-DISHES, &c.

No. 923,208.

Specification of Letters Patent.

Patented June 1, 1909.

Application filed October 3, 1908. Serial No. 456,086.

To all whom it may concern:

Be it known that I, LOUIS K. SONE, a citizen of the United States, and resident of the city, county, and State of New York, have 5 made a certain new and useful Invention relating to Collapsible Stands for Chafing-Dishes, &c., of which the following is a specification, taken in connection with the accompanying drawing, forming part of the 10 same.

This invention relates to collapsible stands suitable for use with chafing dishes or other cooking utensils and relates especially to the 15 means of connecting the collapsible wire portion of such stand with the sheet metal base and pan holder or support thereof by forming locking flanges on the base and support in which the upper and lower rings of the stands are engaged and securely held as well as protected thereby.

In the accompanying drawings showing in a somewhat diagrammatic way illustrative embodiments of this invention and in which the same reference numeral refers to similar 25 parts in the several figures, Figure 1 is a front elevation of a stand embodying this invention. Fig. 2 is a partial top view of the collapsible wire portions thereof before assembly. Fig. 3 is a partial enlarged front 30 view of the form of connection shown in Fig. 1 and Fig. 4 is a side section thereof. Fig. 5 is a corresponding detail front view showing another form of connection and Fig. 6 is a side sectional view thereof. Fig. 7 is a detail front view showing still another form of 35 connection and Fig. 8 is a side sectional view thereof. Fig. 9 shows another modified form of connection to the support, and Fig. 10 is a side sectional view thereof.

40 * In the illustrative embodiment of this invention shown in Figs. 1, 2, 3 and 4 the collapsible wire portion of the stand may have the same general construction indicated in my copending application 360,023, filed 45 March 1, 1907, the substantially U-shaped members 5 of wire or the like being connected together by suitable clamping means, such as the soldered or otherwise fastened wire clamps 7 which may if desired join suitable narrowed portions of the U-shaped 50 members to insure alinement thereof. The outer ends of the legs of these members may be yieldingly connected to suitable rings 2, 3 of wire or other material by forming, for example, suitable hooks or connecting portions 55 13 in the legs which may completely inclose or otherwise sufficiently engage the rings and allow the members to swing to the desired extent in opening and closing the stand.

In order to more securely hold the stand 60 in its extended position indicated in Fig. 1, suitable locking means may be provided on the U-shaped members such as lugs or stops 24 on the legs of the U-shaped members to engage with the coöperating legs 6 of the adjacent members so as to prevent any further collapsing movement when the members have been extended and their connected clamping members 7 swung inward into the position shown in Fig. 1. 70

It is desirable for some purposes to have the wire extensible stand connected to a metal support or pan holder 1 to coöperate with the chafing dish or other utensil and also if desired with a suitable sheet metal 75 base, such as 8, formed of any desired material. The support 1 for example which may be formed by stamping, spinning or otherwise and of any ornamental design may be connected with the extensible wire portion of the stand by forming a suitable locking flange 10 on the support by spinning or otherwise so as to provide a suitable recess in which the upper ring 3 may be held, suitable hook slots 12 of any suitable shape being 80 preferably formed in this locking flange 10 and also if desired in the adjacent portions of the support to accommodate the hooks which are preferably brought closely together to minimize the number of slots to be 85 formed. The parts may be conveniently assembled by loosely inserting the hooks into their slots and then bringing the free ends of the ring 3 together and permanently holding them tightly by any desired means so as to 90

95 clamp the hooks and connected U-shaped members and lock the ring, hooks and connected U-shaped members permanently to the support while allowing the desired freedom of movement between them. For this 100 purpose the free ends 14, 15 of the ring may be provided with screw threads to be engaged by the turn-buckle 9 as indicated in Fig. 2 so that the ring can be brought together to engage the locking flange of the 105 support with the desired degree of force, and the turnbuckle and coöperating portions of the ring may then be soldered, riveted or otherwise permanently secured in any desired manner. 110

It is of course to be understood that it is not necessary in all cases to employ turn-buckles for bringing the rings together as other means may be used before the ends 5 of the rings are fastened as by soldering, riveting or otherwise, and also the locking flanges may be spun or otherwise forced around the rings to more thoroughly secure these parts, as is indicated in Fig. 6. A 10 similar spun locking flange 11 may be formed on the base 8 and the ring 2 similarly secured therein, the hooks 13 also lying if desired in suitable hook slots 12 formed in the flange and adjacent parts of the base if 15 desired. This base which may be formed of spun or stamped sheet metal or other material of course may be fastened in any desired way to the plate or box of the traveling cooking utensil of my United States 20 application 422,085, renewed March 19, 1908.

If desired, the hook slots may not only be formed in the flange itself, but also in the adjacent portions of the support and base as 25 indicated in Figs. 5 and 6 in which the hook slots 19 are shown of sufficient extent to accommodate the hooks 13 of the U-shaped members 5 so as to allow the ring or bearing member 17 on which the hooks play to lie 30 snugly against the metal of the support. The locking flange 18 may also as indicated be forced substantially around the wire ring 17 so as to still more firmly hold the same in 35 position and under these circumstances it is not of course necessary to have such strong connections between the free ends of the ring. If desired also the locking flange on the support or base may be spun or otherwise formed into a substantial bead 20, as 40 indicated in Figs. 7 and 8, having sufficient strength to properly support the hooks 13 on the U-shaped members, suitable slots 21 being preferably formed in the adjacent metal so as to properly accommodate the 45 wire members and allow the desired freedom of movement therein. Also, if desired the locking flange 10 on the support may for example be used to support the hooks 13 of the U-shaped members 5 which are inserted 50 through suitable slots 22 and if desired the locking flange may be locally reinforced by bending over the material displaced to form

the slot 22 so as to form a reinforced bearing portion 23.

Having described the invention in this 55 case, in connection with a number of illustrative embodiments thereof, to the details of which disclosure the invention is not of course to be limited, what is claimed as new and what is desired to be secured by Letters 60 Patent is set forth in the appended claims.

1. In cooking utensils, two sets of substantially U-shaped members connected by clamping means at their reduced portions and having locking means on their legs to 65 prevent their collapsing, rings engaged by hooks formed on the free ends of said members, turn-buckles adjustably connecting the free ends of said rings, a support and base of sheet metal formed with locking flanges ac- 70 commodating and permanently connected one to each of said rings and formed with hook slots in said locking flanges and adjacent material, each of which accommodates a plurality of said hooks. 75

2. In cooking utensils, a plurality of substantially U-shaped members connected by clamping means, rings engaged by hooks formed on the free ends of said members and connectors joining the free ends of said rings, 80 a support and base of sheet metal formed with locking flanges accommodating and permanently connected one to each of said rings and formed with hook slots to accommodate said hooks. 85

3. In collapsible supports, a plurality of sets of connected substantially U-shaped members, rings engaged by hooks formed on the free ends of said members, a support and base formed with locking flanges accommo- 90 dating and permanently connected one to each said rings. 95

4. In collapsible supports, a plurality of sets of flexibly connected members, a support provided with slots, hooks on one of said sets of members located in said slots and laterally aligned thereby and connecting means co-operating with said hooks and permanently connecting said hooks and members to said support.

LOUIS K. SONE.
